United States Patent Office

Des. 185,715

Patented July 21, 1959

185,715

PLASTIC COATED FABRIC

John M. Little, Toledo, Ohio, assignor to The Landers
Corporation, Toledo, Ohio, a corporation of Ohio

Application December 11, 1957, Serial No. 48,866

Term of patent 14 years

(Cl. D87—3)

FIG. 1.

FIG. 2.

FIG. 3.

Fig. 1 is a plan view of a plastic coated fabric embodying my new design;

Fig. 2 is an enlarged fragmentary view of the plastic coated fabric shown in Fig. 1; and

Fig. 3 is a section taken on line 3—3 in Fig. 2 to show the direction and extent of the embossing which forms the fabric surface.

I claim:

The ornamental design for a plastic coated fabric, substantially as shown.
